TOILET

Filed Oct. 19, 1932

UNITED STATES PATENT OFFICE

2,073,390

TOILET

Catherine T. Giblette, Detroit, Mich.

Application October 19, 1932, Serial No. 638,589

11 Claims. (Cl. 4-137)

My invention relates to improvements in toilets; and the objects of my improvement are, first to provide a toilet especially adapted for the use of infants or invalids; second, to provide a toilet enclosed in a container of the portable type; third, to provide a toilet provided with means for preventing contents and odors from escaping therefrom; fourth, to provide a toilet having a movable protective device between its cover and vessel; fifth, to provide a toilet having a deflector means; sixth, to provide a toilet with liquid tight compartments therein; seventh, to provide a toilet having a closed container with foldable arm members contained therein when folded; eighth, to provide a toilet having a cover adapted for compressing a gasket against the vessel of the toilet; ninth, to provide a toilet assembly having the appearance when closed of a compact suit case; tenth, to provide a toilet housing having one of its sides formed by an air tight compartment provided with a hinged door; eleventh, to provide a toilet having a cover positioned by hinge members adapted for use as hand or arm rests; twelfth, to provide a lining member adapted to operate as a hinge member; thirteenth, to provide a toilet assembly having a compartment for storing a deflector member therein when said deflector is not in use; fourteenth, to provide a toilet housing having means for holding a cover member or a deflector member therein; and fifteenth, to provide a toilet with arm or hand rests having a shock absorbing covering thereon.

I attain these objects by the mechanism illustrated in the accompanying drawing, in which:—

35 Figure 1 is a perspective view of the toilet in an open position; Fig. 2, a perspective view of the toilet in a closed position; Fig. 3, a sectional view of the toilet taken on the line 3—3, Fig. 2; Fig. 4, a side elevation of the protective member for 40 the cover of the toilet; Fig. 5, a sectional view of a portion of the toilet on the line 5—5, Fig. 1; Fig. 6, a side elevation of the deflector member; Fig. 7, a sectional view of the deflector member taken on the line 7—7, Fig. 6, said sectional view 45 disclosing by dotted lines, the parts associated with said deflector member; Fig. 8, a sectional view of the deflector member in its compartment in the toilet, said sectional view being taken on the line 8—8, Fig. 1; Fig. 9, a side elevation of the 50 hinge portion of one of the folding arms of the toilet; Fig. 10, a plan view of the hinge portion of the folding arm disclosed in Fig. 9; Fig. 11, a side elevation of one of the folding arms in its folded position; Fig. 12, a sectional view through 55 a portion of a compartment door and lining mem-

bers therefor; and Fig. 13, a sectional view of one of the hinge members to disclose its cross sectional construction.

Similar numerals refer to similar parts throughout the several views:—

The toilet assembly A is designed for use as a portable unit for use in travelling and also for use for invalids. The toilet assembly A may be constructed with the housing portion B which may be made, as disclosed, in the form of a small 10 suit case which can be easily and securely carried in an inconspicuous way and can be easily and quickly made ready for use by opening the cover or lid of the case.

The toilet housing B may be made of wood, 15 leather, wicker material, or any other suitable material, said housing preferably being constructed of a light and sturdy material that will render the toilet assembly A easily handled or carried and at the time provide a secure support 20 for the toilet seat and associated parts.

The housing B is constructed with the end walls 1 and 2, the side wall 3 and the bottom wall 4, the other side wall being formed by the walls of the compartment 5 as hereinafter disclosed, 25 said walls being suitably and securely fastened together to provide a sturdy construction. The toilet housing B is provided with the upper wall portion 6 which is provided with the opening 7 extending therethrough and connecting with the chamber 8 inside of the toilet housing B. The shape of the opening 7 is such that the vessel or 30 pan 9 will assemble therein, the body of the vessel 9 extending into the chamber 8, the vessel 9 being provided with the flange 10 around its peripheral edge, the flange 10 fitting within the recess 11 of the upper wall portion 6, the recess 11 extending around the edge of the opening 7, the flange 10 thus supporting the vessel 9 on the upper wall portion 6. The vessel 9 may be constructed with an elliptical shape or of any other 35 desired shape, and said vessel may also be provided with an irregular portion 12 forming a spout or funnel shaped extension to permit the contents of the vessel 9 to be easily poured or emptied therefrom, the flange 10 being formed to extend around the edge of said irregular portion 12 to form a continuous flange 10 around the entire periphery of the vessel 9.

The upper wall portion 6 may be provided with 40 the recesses 13 to extend under the flange 10 and connect with the opening 8.

The recesses 13 may be of suitable length to 45 permit the fingers of the hand to be inserted under the flange 10 to permit the vessel and its 50

5

50

55

contents to be easily lifted and removed from its supported position in the toilet assembly A. The recesses 13 may also be constructed, if desired, to extend under the flange 10 sufficiently only to 5 permit room for a finger hold on the flange 10, the recesses 13 thus stopping short of the opening 8.

The edges of the recesses 13 will be rounded to prevent any injury to the hands.

10 The upper wall portion 6 is provided with the holes or recesses 14, one of which is shown in section in Fig. 5. The holes 14 may be closed at their lower ends as shown or they may extend through the wall portion 6. The holes 14 are 15 located in positions adjacent the peripheral edge of the flange 10 of the vessel 9. The cover member 15 is constructed of suitable material such as rubber composition or similar material which may be secured between two surfaces to prevent 20 liquids or gases from passing thereby. Also it is preferable to construct said cover member 15 of suitable material as will permit of ready cleansing and renovating without injury to same.

The cover member 15 is provided with the extensions 16 which are adapted to fit within the holes 14 of the upper wall portion 6 to locate the cover member in a fixed position relative to the vessel 9. The cover member 15 will extend over the upper surface of the flange 10 of the vessel 9 and also over portions of the upper surface of the wall portion 6 thus forming a cover to prevent any of the contents of the vessel 9 from splashing out against the surface 17 of the cover 18 which is hinged at 19 to the toilet housing B. 30 The cover 18 is provided with a portion 20, which may extend from the surface 17, and which is adapted to contact and clamp securely a portion of the cover member 15 against the upper surface of the flange 10 of the vessel 9, the portion 40 20 of the cover 18 being located to extend in conformity with the general shape or contour of the flange 10, the portion 20 being of such a shape and cross section as will present no sharp corners or edges to injure a person leaning against 45 the surface 17, the portion 20 being joined to the surface 17 by sufficiently curved surfaces to accomplish same.

When the cover 18 is in its closed position, as shown in Figs. 2, 3, and 5, the portion 20 thereof 50 will clamp the cover member 15 securely against the upper surface of the flange 10 of the vessel 9 and not only prevent any of the contents from splashing out of the vessel 9 but also will prevent any odors or gases from escaping therefrom, the 55 clamping action of the portion 20 deforming the material of the cover member 15 as a gasket member to provide an air tight seal around the flange 10, the upper surface of said flange 10 being constructed approximately level and smooth to 60 aid in maintaining the air tight seal.

The cover 18 may be secured in its closed and sealing positions by suitable locking members indicated at 21 on the housing B and at 22 on the cover 18. The cover 18 may be pivotally moved 65 on the hinges 19 to the open position, as disclosed in Fig. 1, in which position the cover 18 may be used as the back support of the toilet housing B when said housing is used as a chair, the cover 18 being limited to a predetermined position by 70 the hinge members 23 and 24 which are preferably constructed of a section presenting no sharp edges in order that said hinge members 23 and 24 may be used as hand or arm rests when said housing B is used as a chair. Also to facilitate 75 the use of the members 23 and 24 as hand or

arm rests, the central portion 25 of said members may be covered with rubber composition or similar material which will not only afford a shock cushioning means but also a more comfortable hand rest or grip means, said construction 5 of said members being disclosed in the cross section of one of said members, Fig. 13.

The upper wall portion 6 of the housing B is constructed with cut away portions at each of its sides to form the ledges 26 which extend to 10 the surfaces 27 which may be located at the required distance from the outside of the housing B to permit the members 23 and 24 to move to their folded positions, as disclosed in Figs. 3 and 11 in which positions the members 23 and 24 extend adjacent one another, one of said members extending adjacent the surface 27 and one of said members extending adjacent the inner surface of the flanges 28 which is suitably attached to the cover 18, said flanges 28 extending to a position 20 adjacent the ledges 27 to effectually cover and hide from view, the members 23 and 24 when the cover 18 is in its closed position. It is to be noted that the flanges 28 should be constructed with no sharp corners or edges to injure a person in using 25 the toilet assembly B. The ledges 26 extend for a portion only of the length of the sides of the housing B, the length of said ledges 26 being sufficient to receive there adjacent, the members 23 and 24 in their folded positions. Similarly the 30 flanges 28 extend for a portion only of the length of the sides of the cover 18, the length of said flanges being sufficient to fit within the length of ledges 26 and to effectually hide the members 23 and 24 from view when the cover 18 is in its closed 35 position in the toilet assembly A. The members 23 and 24 are pivotally connected by a rivet 29 or other suitable means while the member 24 is pivotally connected to the portion, of the housing B, adjacent the surface 27 by a pin 30 or other 40 suitable means. The member 23 may be provided with the offset portion 31 and the flattened portion 32 for pivotally fastening said member 23 to the member 24, said member 24 being provided with a similar flattened portion 33, the flattened 45 portions 32 and 33 and the offset portion 31 permitting the members 23 and 24 to move adjacent each other to their folded positions as disclosed in Figs. 3 and 11.

Each of the members 23 is pivotally connected 50 to one of the flanges 28 by a pin 34 or other suitable means. The member 24 is provided with the radial portion 35 which facilitates the movement of the member 23 from its upright position, as disclosed in Figs. 1 and 9, to its folded position, 55 as disclosed in Figs. 3 and 11. Also the member 24 is provided with the extension portion 36 which is provided with the surface 37 which contacts with the surface of the ledge 26, when the members 23 and 24 are in their open or unfolded positions, as disclosed in Figs. 1 and 9, the extension portion 36 thus limiting the opening movements of the members 23 and 24 which in turn limits the opening movement of the cover 18 and provides means for supporting the cover 18 in a predetermined open position when a person uses the cover 18 as the back of a chair.

The housing B is provided with the compartment 5 which may be of sufficient length to accommodate the door 38 which is provided with 70 the hinges 39, the door 38 thus being located so that it forms the outside wall of the housing B. The inside wall of the compartment 5 is formed by the wall portion 40 which extends adjacent the wall of the vessel 9. The ends of the compartment 75

ment 5 may be formed by the end walls 1 and 2 of the housing B, the top wall of the compartment 5 may be formed by the upper wall portion 6 and the bottom wall of the compartment 5 may be formed by the bottom wall 4. The compartment 5 is provided with the lining 41 which is preferably constructed of water proof material such as rubber composition or of similar material, said lining 41 thus permitting the compartment 5 to be used for the storage of the usual infant's or invalid's fabric or other materials when damp without injury to the housing B and without the inconvenience of carrying such materials separately. A portion of the lining 42 10 may be secured to the door 4 as disclosed in Figs. 3 and 12, the lining 42, which is secured to the door 4, extending under the lining 41 which is secured to the inside of the wall 4. Thus the lining 42 can movably operate with the door 4 due to the resilient material used for the lining, the lower portion 43, of the portion 42, forming a second hinged lining member that will effectually prevent any leakage from the compartment 5 at 15 its lower portion. Also the lower portion 43 of the lining 42 may be extended up the sides of the ends of the compartment 5 as indicated at 44, said portions 44 being attached to the inside wall surfaces of the ends of the compartment 5 at 20 points adjacent the door 38 so that the lining 42 may be stretched by the opening movement of the door 38 to form the portions 45, as disclosed by dotted lines in Fig. 1, when the door 38 is opened, the portions 45 effectually preventing any leakage from the compartment 5 past the 25 ends of the door 38, the portions 45 tending to form hinge portions which may be utilized to tend to resiliently close the door or the portions 45 may be provided with folded or convoluted portions to maintain closed ends for the door 30 when open without exerting any tendency to close the door. Also the portions 45 and the portions 43 may be carried to a partial portion of the height as shown or they may be extended to the upper wall portion 6. Also the lining 41 may 35 be provided with the extension portion 46 which forms a resilient gasket member which resiliently contacts the upper portion of the door 38 in its closed position to seal the door 38 at its upper side, as disclosed in Fig. 3, to further prevent 40 any leakage from the compartment 5 even when the toilet assembly A is carried or handled in various positions. The door 38 may be provided with suitable locking means as indicated at 47 and also with a handle means as indicated at 48. The toilet assembly A is provided with the handle 49 to permit the toilet assembly A to be 45 easily handled and carried.

The deflector member 50, disclosed in Figs. 6 and 7, is provided for the use of male infants 60 to prevent soiling or injury to the toilet assembly A or to the clothes of the infant, the deflector member 50 being so constructed as to provide the chamber or recess 51, the walls 52 of the recess 51 being inclined and extended on three of its 65 sides to the curved wall portion 53 at their upper ends, the chamber 51 being open on its side facing the vessel 9. The deflector member 50 is provided with the curved flange portion 53' which fits snugly into the irregular portion 12 of the 70 vessel 9, the deflector member 50 being further provided with the extension portion 54 which fits into one of the recesses 14 in the upper wall portion 6 of the housing B, the recess 14 being used 75 for this purpose being the one at the front of the toilet assembly B and adjacent the irregular

portion 12 of the vessel 8. The dotted lines in Fig. 7, indicate the relative position of the vessel 8 and the deflector member 50 assembled therewith. The deflector member 50 is preferably made of resilient and liquid proof material such as rubber composition or similar material. The extension portion 54 together with the curved flange 53' will maintain the deflector member 50 in an upright stable position, the extension portion 54 fitting within the recess 14 in a similar manner to the extension 16 of the cover member 15. The housing B is provided with the recess 54' which is formed with the wall portions 55 which connect with the upper wall portion 6. The recess 54 is lined with a liquid proof lining 56 in a similar way to the compartment 5, the lining 56 being provided with a flange portion 57 extending adjacent the edge of the recess and adjacent the upper surface of the upper wall portion 6. The closed lower end of the recess 54' is provided with a curved shape to conform to the curved wall portion 53' of the deflector member 50 which is stored within the recess 54', as indicated by dotted lines in Fig. 8, when said deflector member 50 is not in use as a deflector means.

It is to be noted that I have thus provided, in my invention, a toilet which is readily portable for the use of infants and invalids when travelling in automobiles, railways, etc. where it is desired to provide a safe, sanitary, and inconspicuous unit for such purposes. The general external appearance of my invention may be that of a compact and attractive suit case while the general inside appearance may be that of a compact and efficient chair or seat unit, the inside appearance being readily adapted to be presented in dainty bathroom colors and designs which will appeal to the mothers of infants or those who are responsible for the care of invalids. The toilet assembly A is readily converted to its open position in which it is ready for use, by unfastening the cover 18 and pivotally moving it on its hinges 19 to its maximum open position, as disclosed in Fig. 1, in which position the cover 18 will be automatically locked and supported by the members 23 and 24 as hereinabove described. 30 35 40 45

members 10 and 14 as hereinabove described. The cover member 15 is readily removed and after the toilet has been used, the cover member 15 is replaced in position and the cover 18 is again fastened in its closed position whereupon the toilet assembly A is again ready for portable use without the necessity of emptying the vessel 9, said toilet assembly A being automatically closed to provide an air tight case from which the contents of the vessel 9 cannot leak and at the same time preventing any odors escaping therefrom. The use of the cover member 15 insures the inside surface 17 of the hinged cover 18 being always free and clean from any splash or soiling from the contents of the vessel 9 and permitting at all times the use of the cover 18 as a rest support without soiling or injury to the clothes of the infant or invalid. When the toilet assembly A is cleaned at the end of the journey or at any other convenient time, the cover member 15 may be scoured, washed, or renovated for use again when required.

The members 23 and 24 which are ordinarily used as arm rests or hand grips may be omitted, if desired, when the toilet assembly A is used for adult invalids, the cover 18 being allowed to move to a fully open and reclined position or suitable supports may be added to limit its movement to any desired open position. The cover 75

member 15, if desired, may be also hinged in a similar manner to that of the cover 18 but it is believed that the removable cover member 15, as disclosed, will prove to be the more popularly desired method of using same.

It is also to be noted that the toilet assembly A will be provided, wherever possible with generous radii, as indicated at 55' to provide freedom from sharp corners and edges. Also a suitably mounted resilient member 56' may be provided to tend to maintain the cover 18 in its open position to prevent accidental closure of the cover 18.

It is also to be noted that the flange 57 of the lining 56 may be slightly raised above the adjoining surface of the upper wall portion 6 to provide a gasket portion to be compressed by the cover 18 when in its closed position to render the recess 54 air tight to prevent any escape of liquid or odors that may accumulate from storing the deflector member 58 in the recess 54', the compressing of the flange 57 being similar to that in which the cover member 15 is compressed by the portion 28, the flange 57 being raised sufficiently above the surface of the upper wall portion 6 to permit the cover 18 to contact said flange 57 sufficiently to render the recess or chamber 54' air tight without providing another extension portion, similar to 20, thus preserving a more balanced appearance of the cover 18.

I claim:

1. In a toilet provided with a vessel having a flange around its periphery, the combination of a housing provided with a chamber having an opening in one of its sides, said housing being provided with a recess for receiving the flange of said vessel, said housing being provided with recesses adjacent the flange of said vessel to permit the insertion of a portion of a hand of a person therein to lift said vessel, said housing being further provided with a plurality of recesses, a flexible cover member provided with extension portions fitting in the recesses of the housing, said cover member extending over the vessel, said cover member contacting the flange of said vessel, a cover hinged on said housing, said cover being provided with an extension portion for compressing said flexible cover member against the flange of said vessel when said cover is in its closed position, and hinge members connected to said cover and said housing, said hinge members being foldable below the upper surface of said housing, said hinge members being adapted for use as arm rests.

55. 2. In a toilet, the combination of a vessel having an open side and provided with an irregular portion forming a spout together with a flange extending around said vessel and its spout, a housing provided with an opening for receiving the vessel together with its irregular portion forming a spout, said housing being further provided with a depression provided with a depressed surface having a shoulder having a height substantially equal to the thickness of said flange of said vessel, a resilient member covering the open side of said vessel, said resilient member extending over the flange of said vessel and over the shoulder of said depressed surface of said housing, and cover means for closing the housing and maintaining said vessel in its assembled position in said housing.

70. 3. In a toilet, the combination of a housing provided with an opening, a vessel extending through said opening and provided with a flange engaging the edge portions of the opening of said

housing, a resilient member covering said vessel, and a cover member suitably mounted and provided with a portion, having a similar shape to that of the flange of said vessel, for compressing said resilient member into contact with the flange of said vessel.

4. In a toilet, the combination of a vessel having an open side, means for supporting said vessel, said means being provided with a plurality of recesses closed at one of their ends and adjacent said vessel, a cover member provided with a plurality of projections engaging the closed recesses of said means to fix said cover member in its assembled position, said cover member extending across and contacting the upper surface of said vessel adjacent its periphery to fully close the open side of said vessel, and a second cover suitably mounted and adapted to engage said first mentioned cover member only at points adjacent the open side of said vessel.

10. 5. In a toilet, the combination of a housing, an open vessel supported adjacent its open side in said housing, a cover pivotally supported on said housing and provided with an embossed portion, and a removably mounted flexible member interposed between the open side of said vessel and said cover to close the open side of said vessel, said flexible member being contacted by the embossed portion of said cover.

15. 6. In a toilet, the combination of a housing, a vessel mounted in said housing, a resilient member covering said vessel, and a cover member provided with a raised portion for engaging said resilient member solely at points adjacent the edge of said vessel to cause said cover member to concentrate pressure for compressing said resilient member against said vessel.

20. 7. In a toilet, the combination of a housing, a vessel mounted in said housing, a resilient member closing said vessel, and a member covering and engaging said resilient member, said last mentioned member being provided with a projecting portion extending longitudinally in a path conforming substantially to the shape of said vessel for concentrating pressure to force said resilient member into engagement with said vessel.

25. 8. In a toilet, the combination of a housing provided with a chamber provided with a wall portion having an opening therein, a vessel extending through said opening and having a peripheral flange for supporting said vessel on said housing, a flexible cover member covering and closing said vessel, and a second cover member provided with an embossed portion having a shape conforming substantially to the peripheral flange of said vessel and adapted to contact and compress said flexible cover member against the peripheral flange of said vessel.

30. 9. In a toilet, the combination of a housing having a wall portion provided with an opening therethrough, said wall portion being further provided with a plurality of holes therein, an open vessel extending through the opening of said wall portion and having a flange for engaging the upper surface of said wall portion to support said open vessel, a resilient member extending over the open side of said vessel to close it and prevent the contents of said open vessel from passing out of said open side, said resilient member being provided with extension portions fitting in said plurality of recesses of said wall portion, and means for compressing said resilient member against said open vessel.

35. 10. In a toilet, the combination of a housing

provided with a supporting wall portion, a vessel having an open side and mounted on and extending through the supporting wall portion of said housing, a cover member pivotally mounted 5 on said housing and provided with an embossed rib portion, and a gasket member interposed between said vessel and said cover member to close said vessel and to prevent the contents of said vessel from contacting said cover member, said 10 gasket member having its central portion extending across the open side of said vessel, said gasket member having an area equal to or exceeding the projected area of the uppermost portion of said vessel, said gasket member being contacted 15 by said embossed rib portion of said cover member pivotally mounted on said housing.

11. In a toilet, the combination of a vessel provided with an open side together with a flange

theretofore, a housing having a wall portion supporting said vessel, the uppermost surfaces of said wall portion and said flange being substantially flush with one another, a cover member pivotally mounted on said housing and provided 5 with a relatively narrow embossed portion of substantially the same shape as the flange of said vessel, and a flexible member extending between said vessel and said cover member to cover the total area of said open side of said vessel and 10 said flange to close said vessel to prevent the contents of said vessel from contacting said cover member, said flexible member being forced to engage the flange of said vessel by said embossed portion of said cover member with a maximum 15 pressure.

CATHERINE T. GIBLETTE.
